CLAIM

The ornamental design for a mobile computing device, as shown and described.

DESCRIPTION

FIG. 1 is a perspective view of a mobile computing device, showing a first embodiment of our new design;

FIG. 2 is a view of a first end of the first embodiment;

FIG. 3 is a left side view of the first embodiment;

FIG. 4 is a top view of the first embodiment;

FIG. 5 is a right side view of the first embodiment;

FIG. 6 is a view of a second end of the first embodiment;

FIG. 7 is a bottom view of the first embodiment;

FIG. 8 is a perspective view of a mobile computing device, showing a second embodiment of our new design;

FIG. 9 is a view of a first end of the second embodiment;

FIG. 10 is a left side view of the second embodiment;

FIG. 11 is a top view of the second embodiment;

FIG. 12 is a right side view of the second embodiment;

FIG. 13 is a view of a second end of the second embodiment; and,

FIG. 14 is a bottom view of the second embodiment.

Broken line areas in the figures form no part of the claimed design and are for illustrative purposes only.
